UNITED STATES PATENT OFFICE.

DAVID L. DWINNELL, OF MONTREAL, QUEBEC, CANADA, ASSIGNOR OF ONE-HALF TO MILLER BROTHERS & MITCHELL, OF SAME PLACE.

WATER-CLOSET.

SPECIFICATION forming part of Letters Patent No. 415,961, dated November 26, 1889.

Application filed August 23, 1889. Serial No. 321,790. (No model.)

To all whom it may concern:

Be it known that I, DAVID LANCASTER DWINNELL, a citizen of the United States of America, residing at the city of Montreal, in the District of Montreal and Province of Quebec, Canada, have invented new and useful Improvements in Water-Closets; and I do hereby declare that the following is a full, clear, and exact description of the same.

10 This invention relates to improvements in that part of a water-closet by which the "bowl" or "hopper" of the closet is "flushed" with water; and the object of my invention is to construct this part of the apparatus in 15 a more simple, cheap, and durable manner.

The particular construction and combinations of elements which form the present invention will be hereinafter set forth and claimed.

20 In the drawings hereunto annexed similar letters of reference and numerals indicate like parts.

Figure 1 is a front elevation, part in section, of an apparatus embodying my invention. Fig. 2 is a vertical central section of the obstructor D. Fig. 3 is a plan of the obstructor D as viewed with the cap 4 removed. Fig. 4 shows a first modification of the siphon A. Fig. 5 is a further modification of the siphon A. Fig. 6 shows a modification of the obstructor D. Fig. 7 is a further modification of the obstructor. Figs. 8, 9, and 10 show modifications of the exhauster E.

For the sake of clearness and brevity and 35 to avoid multiplicity of terms I shall in this specification establish the following meanings to the following words:

By the word "siphon" will be understood any known construction which will from 40 its nature fulfill the office of a siphon.

By the word "obstructor" will be understood any valve, trap, or other ordinary known means by which the atmosphere is prevented from returning to a space from which 45 it has been more or less exhausted by any suitable means.

By the word "exhauster" will be understood any known contrivance arranged so that an amount of rarefaction of the atmosphere in a given space may be produced.

Letter A is a siphon, which may be arranged in any ordinary manner to draw off the water from a tank B before said tank is full to overflowing. The long leg 1 of the siphon is extended down and connected with the 55 bowl or hopper C, while the short leg 2 is arranged to draw off the water in the said tank to a level near the bottom of the tank.

D is the obstructor, and E is the exhauster.

As shown in Figs. 2 and 3, the obstructor 60 consists of a small vessel made in two parts, of which 3 is the body, and 4 the cap or cover. These are made integral with the siphon-leg 1, and are screwed together, as shown, being fitted to form an air-tight joint between 65 them. Within the body 3, by means of projections 5, which may be made integral with the body, is held a cup 6. This is soldered to the ends of the projections 5, or, if desired, the projections 5 may be formed on the cup 70 6 and soldered to the body 3, or the cup may be secured in any other ordinary manner in the relative position shown. The cup will be of such outer diameter that the spaces 7 about it will be in area somewhat greater than the 75 area of the leg 1. In the cup is placed a hollow rubber or other light ball 8, which floats in the water in the cup and forms an air-tight joint with the leg 1 above it.

When the water comes down the leg 1 to 80 flush the bowl or hopper C, the ball 8 is driven on one side or downward in the cup, and the water passes in the manner indicated by the arrows in Fig. 2.

The obstructor D may, like the siphon, be 85 made in a great variety of ways. As shown in Fig. 6 it consists of a trap 9, which is provided with an air-pipe a, to prevent the whole of the water from being siphoned out of the trap, and in this case, for the reasons herein-after mentioned, I provide a small perforation 10 in the short leg 2 of the siphon.

In Fig. 7 the obstructor is formed on the extreme end of the leg 1, where it enters into the flange or neck 11 of the bowl C. In this 95 case, as shown, it consists of a flap-valve 12, hinged at 13.

The exhauster D, as shown in Figs. 1 and 6, consists of an ordinary hollow compressible rubber bulb 15—such as are used on injectors 100

and syringes—attached on a pipe 14, which forms a passage from the bore of the leg 1 to the bulb 15.

As shown in Fig. 8, the exhauster is made 5 substantially like a pair of bellows. Here 16 are two heads, one of which is attached on the end of the pipe 14. 17 is an air-tight cylinder of flexible material attached air-tight 10 on each head. 18 is a spiral spring arranged so that when the exhauster has been compressed to bring the heads 16 nearer together it will cause the exhauster to expand again of 15 itself to the fully-extended state shown in Fig. 8.

15 In Fig. 9 the exhauster is formed of a cylinder 19, to which the pipe 14 is connected. Over the front end of the cylinder is attached a rubber diaphragm. By pushing the center part of this diaphragm into the cylinder, as 20 indicated by the dotted lines in the figure, it will return of itself to the position delineated by solid lines.

In Fig. 10 a cylinder 21 is attached on the end of the pipe 14. This is provided with a 25 piston 22, which is pressed and moved in the direction of the arrow by pressing on the knob 23, and is caused to return to the front end of the cylinder or move in the opposite direction to the arrow by the spiral spring 24.

30 The tank B is filled with water to an equal standard or constant normal level after each time the siphon A has operated by an ordinary "ball-cock" F, or any other ordinary contrivance as heretofore in use, and this will be 35 so arranged that the water will not rise in the tank B to such a level as to cause the siphon to act; but the nearer the ball-cock is arranged to allow the tank to fill to the level at which the siphon will act the more easily will the 40 invention work.

To fill the cup 6 with water it is only necessary to press down the ball of the ball-cock F by hand and allow the tank B to fill until the siphon A acts by the increased 45 height of level of water. When the water has once passed down the leg 1, the cup 6 will remain full of water and the ball 8 will float up and close the end 25 of the leg 1 above it. If the exhauster is now compressed, the air contained in it will rush into the leg 1 and the ball 8 (if arranged as shown in Fig. 1, or flap-valve 12, if arranged as shown in Fig. 7) will 50 yield and allow the air to pass out. When the exhauster E again expands, the ball 8 or flap-valve 12, as the case may be, closes and 55 prevents the air from returning. This causes a rarefaction of the air contained within that part of the siphon which lies between the obstrucer D and the level of the water in the siphon-leg 2. This rarefaction causes the siphon to act at any time that the tank B is 60 full of water to the proper level and the exhauster is compressed and expanded.

In the modification shown in Fig. 6, as before remarked, the obstrucer is formed of an ordinary trap 9, and when the exhauster is

operated it would were no provision made only cause the water in the short leg 2 to be pressed down and the water in the trap 9 to be pressed up into the leg 30, and when the 70 exhauster had again expanded these would return to the position from which they had been pressed probably without causing the siphon to operate, unless the exhauster were made of considerably-increased capacity. To 75 obviate this the small perforation 10 is provided at a little distance below the standard level of the water in the tank B, so that as soon as the water falls in the leg 2 (by reason of the compression of the exhauster) to the 80 perforation 10 the air will escape by it, and when the exhauster again expands it will produce the necessary exhaustion to cause the siphon A to act. Now some discretion is necessary with regard to the size of the perforation 10, as if made too large it will destroy the 85 action of the siphon A, and if made too small the air will take too long to escape. Therefore without confining my invention in any way I would say that I have found by practical 90 operation that where the siphon A is formed of one and one-fourth inch (inner diameter) pipe a perforation of from one-thirtieth-second to one-sixteenth of an inch is suitable for the purpose.

95 Almost endless modifications of siphons, exhausters, and obstrucers could be arranged to operate substantially in the manner above described without departing from the gist of my invention, which modifications it would 100 be useless to further describe. Therefore I say that I do not confine my invention specifically to the above-set-forth particulars of construction.

105 What I claim is as follows:

1. The combination, in an apparatus for flushing the bowls and hoppers, &c., of closets with water, of the tank B, supplied with a standard level of water, as described, siphon A, provided with cap 4, and body 3, having cup 6 attached within it, leaving a space for the passage of the water between the said body and cup, ball 8, arranged to float in the cup and form a valve to the end of the upper portion of the siphon-leg 1, with an exhauster arranged to cause an exhaustion within the siphon, the whole substantially as described and shown.

110 2. The combination, with a siphon, of the cap 4, and body 3, having cup 6 inclosed therein, ball 8, arranged to float in said cup and adapted to form a valve to the lower end of the upper part of the siphon's leg 1, the said siphon being further provided with pipe 14, and bulb 15, adapted to form an exhaustion 115 in the siphon, the whole substantially as shown and described.

DAVID L. DWINNELL.
